UNITED STATES PATENT OFFICE.

ALBERT C. TOWNSEND, OF BURLINGTON, KANSAS.

SAFE AND VAULT DOOR PROTECTOR.

Application filed October 14, 1924. Serial No. 743,585.

To all whom it may concern:

Be it known that I, ALBERT C. TOWNSEND, a citizen of the United States, residing at Burlington, in the county of Coffey, State of Kansas, have invented certain new and useful Improvements in Safe and Vault Door Protectors; and I do hereby declare the following to be a full, clear, and exact description of the invention, such as will enable others skilled in the art to which it appertains to make and use the same.

This invention relates to new and useful improvements in appliances for safe and vault doors, and the like, and particularly to means for protecting the same from being broken open by burglars.

The principal object of the invention is to provide a novel and efficient means for discharging a poisonous gas, such as carbon monoxide, or other odorless gas, into the room so that the burglar will be overcome or killed by such gas.

Another object is to provide a device of this character which is arranged to discharge poisonous gas when the combination is moved inwardly or outwardly, after the burglar has bored out and removed the portion of the door surrounding the combination mechanism.

Another object is to provide a mechanism which is arranged to discharge the poisonous gas when an attempt is made to burn out the portion of the door by means of an arc or flame.

A further object is to provide a protecting device of this character wherein the gas is discharged at such a point that the effects of the gas will be practically instantaneous, and wherein it will be difficult for the burglar to ascertain from whence the gas flows.

Other objects and advantages will be apparent from the following description when taken in connection with the accompanying drawings.

In the drawings:

Figure 1 is a rear elevation of a portion of a safe door, equipped with the present invention.

Figure 2 is an enlarged vertical sectional view on the line 2-2 of Figure 1.

Figure 3 is a vertical sectional view on the line 3-3 of Figure 2.

Figure 4 is an enlarged vertical sectional view through the lower portion of the door

and the gas outlet means, on the line 4-4 of Figure 1.

Figure 5 is a vertical transverse sectional view through the gas outlet device, on the line 5-5 of Figure 4.

Figure 6 is a vertical sectional view on the line 6-6 of Figure 2.

Figure 7 is a vertical sectional view through the gas tank.

Referring particularly to the accompanying drawings, 10 represents a portion of a safe door, having the opening 11, in which is mounted the combination mechanism 12.

Secured to the rear face of the door 10, in covering relation to the inner end of said opening 11, is a casing 10', said casing having a central opening 11', within which is disposed the cylinder 13. The combination mechanism is mounted in the door in front of the cylinder 13, and surrounding this cylinder, and threaded thereon, is a sleeve 14. This sleeve is snugly fitted within the opening 11', and has a circumferential slot 15, into which projects a pin 16, carried by the wall of the opening, for the purpose of limiting the rotary movement of the sleeve. Formed longitudinally and centrally through the cylinder 13, is a cylindrical wall 17, having a single opening 18 in its upper side, and slidable within the bore of the smaller inner cylinder 17, is a pipe section 19, having a pair of longitudinally spaced openings 20 and 21, in its upper side for alternate registry with the single opening 18, as said pipe section is slipped inwardly or outwardly. The inner end of the pipe section 19 is disposed within the opening 11', and is closed and secured to the inner end of the combination mechanism 12, whereby as the said combination mechanism is moved

inwardly or outwardly, the pipe 19 will be moved within the wall 17 to register one or the other of its openings 20-21 with the opening 18. Screwed into the outer end of the bore of the wall 17 is one branch of a pipe elbow 22, the other branch being connected with the upper end of the pipe 23, which extends downwardly to a point adjacent the bottom of the door 10, where it is connected with the inner end of the bolt

24. This bolt 24 extends through the lower portion of the door, and has a head 25, on its outer end, which has its inner face spaced from the outer face of the door 10,

100

105

to a degree approximately the thickness of a dime. Formed longitudinally and centrally in the bolt 24, from the outer end, is an opening 26, said opening terminating short of the inner end of the bolt, whereby to give the appearance of an opening or bore extending throughout the length of the bolt, and which will be plugged up by a burglar, who might suspect the presence of poisonous gas. Formed longitudinally through the shank of the bolt 24, and in a circular series surrounding the central bore, are the longitudinal passages 27, such passages extending through the inner end of the bolt, in communication with the pipe 23, and having lateral outlets, at their forward ends, inwardly of the head of the bolt, as shown at 28, whereby the gas will flow out between the outer face of the safe door 10, and the inner face of the head of the bolt. The burglar, after having plugged up the central opening of the bolt 24, will think that he has effectively prevented the escape of any possible gas. The space between the head of the bolt, and the face of the door is, so small as to be practically unnoticed.

The outer wall of the cylinder is formed with an opening 29, while the wall of the opening 11', and the sleeve 14, are provided with similar openings 30 and 31, respectively, all of which are adapted for registry, to permit escape of gas into the interior of the cylinder 13, and to the pipe 23, when the section 19 is moved to register one of its openings with the opening 18.

Mounted on the inner face of the door 10, above the opening 11, is a tank 32, which is divided into an upper smaller compartment 33, for containing a foul smelling gas, such as hydrogen sulphide, or the like, and the lower larger compartment 33', which contains a deadly gas, such as carbon monoxide. In the horizontal wall 34, which separates the upper and lower compartments, there is disposed a check valve 35, which opens toward the lower compartment. The gas in the larger compartment is under high pressure, whereby to maintain the check valve 35 in closed position, and thereby prevent escape of the hydrogen sulphide gas, but when the pressure in the lower compartment is reduced to that of the gas of the upper compartment, the valve will open, permitting the foul smelling gas to flow into the lower compartment.

Connected to the bottom of the lower compartment of the tank 32, is a downwardly extending pipe 36, which is connected to the upper end of the vertical passage 38, in the casing 10'. Formed in the casing 10' and surrounding the opening 11', are the horizontal passages 37, and the vertical passages 39, the latter being connected at their ends to the ends of the passages 37, to form

a continuous passage. The lower end of the vertical passage 38 is connected with the intermediate portion of the upper horizontal passage 37, as clearly seen in Figure 3. The opening 30, is continued upwardly and then horizontally inward, as shown at 31', and communicates with the vertical passage 38.

Formed in the casing 10', adjacent the periphery thereof, is a circular passage 42, which communicates with the passages 37 and 39, by means of the passages 38, 38'. Additional radially extending passages 40 extend inwardly from the circular passage 42, to a passage or space 42', which is formed outwardly of the passages 37 and 39. At the outer angles of intersection of the passages 37 and 39 there are formed openings 37' which establish communication between said passages and the passage or space 42'. In each of the passages 41, as well as in the passages 37 and 39, there are disposed the fusible plugs 43, which normally prevent passage of gas from the passages 40 to the passages 37 and 39, but which will readily melt, upon heat being applied to the outer wall of the case 10', or that wall which lies against the rear face of the door 10, as when a burglar attempts to burn out a portion of the door to remove the combination mechanism.

In the normal position of the device, the openings 20 and 21 are both out of registry with the opening 18, while the fusible plugs are intact, whereby the gas will be confined to the passages 40, and the cylinder 13.

Formed in the casing 10', and surrounding the opening 11', is a circular passage 44 which has communication with the passages 37 and 39, by means of passages 46, which lead from the before-mentioned openings 37'. From the lower side of the passage 44, to the pipe 23, there extends a passage 45, which carries gas from the passages 40, and 37—39, when any of the plugs 43 melt.

It will be noted that the wall of the casing 10' next to the door 10 is thinner than that portion remote from the door, to permit the quicker transmission of heat to the plugs. Burglars often bore a series of holes in the door of a safe, surrounding the combination mechanism, and then remove this part of the door, together with the combination mechanism, thus permitting access to the bolts of the door, through the opening thus formed. Sometimes this portion of the door is removed by means of a hot flame, such as an acetylene torch. In the former method, when applied to a door equipped with the present invention, the burglar grasps the combination mechanism and either pushes same inwardly, into the safe, or pulls same outwardly. In the first instance, the pipe section 19 will be pushed inwardly, within the wall 17, so that the opening 21 will register with the opening 18, whereupon gas

will flow from the cylinder 13, through the pipe 23, and out of the openings 27, of the bolt 24, behind the head thereof. The gas used is one which is odorless, and as the gas issues from the passages of the bolt head, the burglar, who is working with his face in close proximity to the bolt head, will inhale or breathe this deadly gas without knowing it, until finally overcome by it. Seeing the opening in the bolt, the burglar will naturally suppose that the gas will escape therefrom, and proceed to stop up said opening, not noticing the space between the head 25 and the face of the door. Should the burglar, however, be frightened off before completely opening the safe, the poisonous gas will continue to escape, thus filling the room therewith, which would endanger the lives of authorized persons who might enter the room. To avoid this, it is provided, as hereinbefore stated, that when the pressure of the poisonous gas has been reduced to the pressure of the foul smelling gas, the check valve will open, permitting this second gas to flow out through the same path through which the poisonous gas flows, with the result that the person entering the room will instantly detect the odor of the gas and be properly warned to retreat from the room, as well as to be notified of the fact that an attempt has been made on the safe, to open same.

In the event that the burglar attempts to remove a portion of the door by means of a torch, the great heat of the flame will be transmitted to the metal of the casing 10', causing the plugs 43 to melt, thereby freeing the gas from the passages 40, so that such gas will pass into the pipes 37, 39, into the passages 44, and thence into the pipe 23, from whence its escapes from the passages of the bolt 24.

It is sometimes necessary for a properly authorized person to remove the combination mechanism, for the purpose of repairing, or changing the combination. To protect the workman, or other authorized person, from danger of the poisonous gas, it is only necessary to rotate the sleeve 14 until the same is stopped by the pin 16, whereby the openings 29 and 31 are moved out of register with the opening 30. The cylinder 13 may then be unscrewed from the sleeve, without danger of gas escaping, to endanger the life of the workman.

Particular attention is called to the fact that the passages 40, with their fusible plugs 43, are arranged in close proximity to the rear face of the door 10, so that before the flame has penetrated the metal of the casing 10', such metal will have become so highly heated as to cause the plugs to melt, and thereby permit the gas to escape, before the burglar can complete his work. Of course, should the burglar continue his operations,

to penetrate the door, with the flame, more of the plugs will be melted, and the volume of gas greatly increased.

What is claimed is:

1. The combination with the door of a safe and its combination mechanism, of a protector including a container for poisonous gas, and means for releasing the gas upon movement of said combination mechanism in either direction transversely 75 through the door, and means for conveying the gas into close proximity to the front of said door.

2. The combination with the door of a safe and its combination mechanism, of a protector including a container for poisonous gas, of a valve means connected with said combination mechanism and operable upon movement thereof in either direction through the door, for releasing the gas from 85 the container, and a conduit for conveying the gas to a point in front of said door.

3. The combination with the door of a safe and its combination mechanism, of a protector including a container for poisonous gas, a conduit for the gas leading from the container through the face of the door, and a valve means connected with said combination mechanism and operable upon movement thereof for releasing the gas from 95 the container into the said conduit.

4. The combination with the door of a safe and its combination mechanism, of a protector including a container for poisonous gas, a conduit leading from the container to a point adjacent the bottom of the door, a member disposed through the door adjacent the bottom and having a false passage therein and a series of longitudinal passages opening through the inner end thereof 100 and through the side thereof adjacent the other end, and a head on the last-named end of said member spaced a slight distance from the face of the door, and means in said conduit and operable upon movement of the 105 combination mechanism for releasing the gas from the container.

5. The combination with the door of a safe and its combination mechanism, of a protector including a container for poisonous gas, the door having an opening therethrough adjacent the bottom, a member disposed in said opening and having a bore terminating adjacent the inner end and opening through the outer end, an enlarged 115 head on the outer end of said member through the center of which said opening passes, the inner face of the head being spaced a small distance from the face of the door, the body of said member having longitudinal openings therethrough the inner ends of which extend through the inner end 120 of the member while the outer ends extend laterally through the sides of the member inwardly of said head, a conduit between

125

130

the container and said passages, and a valve means connected with said combination mechanism for releasing the gas upon movement of the combination mechanism.

5. 6. The combination with the door of a safe and its combination mechanism, of a protector including a container for poisonous gas, a chamber carried by the door, a conduit between the chamber and the con-

10 tainer, a cylinder within the chamber, a sleeve between the cylinder and the wall of the chamber, the wall of the chamber, the sleeve, and the cylinder having registerable openings, a conduit through the cylinder having an opening in its wall, and a slid able and apertured member in said bore connected with said combination mechanism and movable thereby.

15 7. The combination with the door of a safe, of a protector including a container for poisonous gas, a chamber carried by the door, a conduit between the chamber and the

container, the door having gas containing passages communicating with the said conduit, a passage connecting the first passages, 25 a conduit for delivering gas exteriorly of the door, fusible closures in the passages adapted to release gas to the second passage, and a third passage communicating with the second passage and second conduit.

30 8. The combination with a safe door of concentric passages on the door, gas containing passages between the concentric passages, fusible closures in the gas containing passages for retaining such gas, and a conduit communicating with the inner of the concentric passages and having an outlet through a portion of the door, whereby to discharge gas to the conduit upon fusing of the plugs.

35 In testimony whereof, I affix my signature.

ALBERT C. TOWNSEND.
